UNITED STATES PATENT OFFICE.

ALBERT F. TREMBLAY, OF MONTERREY, MEXICO.

BOTTLE-FORMING MACHINE.

Application filed June 26, 1926. Serial No. 118,731.

The present invention relates to improvements in glass bottle forming machines, and has for an object to provide a compact, circular machine for accomplishing at various 5 stages the blank and finished molding operations through the coordinated use of co-acting mechanisms grouped for easy and convenient control by few operatives.

It is another object of the invention to se- 10 cure simplicity in the construction and operation of the machine, and a much higher speed in the operation through such simplicity.

With the foregoing and other objects in 15 view, the invention will be more fully described hereinafter, and will be more particularly pointed out in the claims appended hereto.

In the drawings, wherein like symbols re- 20 fer to like or corresponding parts throughout the several views,

Figure 1 is a diagrammatic top view showing the various positions assumed by the parts at the several stages.

Figure 2 is a vertical section taken centrally through the machine.

Figure 3 is a top plan view of the circular hollow arm structure.

Figure 4 is a section taken on the line 4-4 25 in Figure 3.

Figure 5 is a top plan view of a guide plate.

Figure 6 is a section taken on the line 6-6 in Figure 5.

Figure 7 is a vertical section, taken on an enlarged scale, showing the mold transferring mechanism.

Figure 8 is a vertical section, taken on an enlarged scale showing the blank mold 40 with the parts in position for pouring.

Figure 9 is a similar view with the parts arranged after blowing of the blank mold.

Figure 10 is a vertical section of the finishing mold after the blank has been trans- 45 ferred thereto.

Figure 11 is a similar view with the blowing apparatus attached to the finishing mold and with the finished bottle shown.

Figure 12 is an enlarged top plan view, 50 partly in section, showing the cam control and associated mechanism.

Figure 13 is an enlarged plan view of the cam.

Figure 14 is an enlarged plan view of the clamping jaws for the molds and the operating mechanism therefor.

Figure 15 is a perspective view showing one member of the clamp jaws.

Figure 16 is a similar view of the com- 60 panion clamp member.

Figure 17 is a section taken on the line 17-17 in Figure 14, and

Figure 18 is a section taken on the line 18-18 in Figure 2.

Referring more particularly to the drawings and for the present to Figure 2, 20 65 designates a track or supporting surface upon which the wheels 21 carrying the machine are arranged to travel. These wheels are carried by a base 22 of hollow construc- 70 tion to which is bolted the air pipe 23.

The base 22 supports the hollow pedestal 24, which in turn supports for rotation the hollow arm structure or spider 25. This hollow arm structure or spider, is shown in 75 Figures 3 and 4, and consists in the hollow arms 26 extending radially out from the central hollow ring 27 having the inturned circular flange 28 at its upper end.

The ring 27 is provided with the openings 80 29 to register with the hollow arms, and at the outer ends the hollow arms are made with bearing openings 30 to receive and support the transfer apparatus, as shown in Figure 7. Further constructional features of 85 the spider or hollow arm construction will be described later in connection with said Figure 7.

To return to Figure 2, the flange 28 of the 90 spider construction is arranged to overlie a shoulder 31 at the upper portion of the hollow pedestal 24 and ball races are provided between these two parts for the anti-friction bearings 32.

The spider construction is rotated upon 95 the pedestal 24 by means of a gear wheel 33 affixed beneath the spider and surrounding the hollow pedestal, with which gear wheel meshes a pinion 34 on the upper end of a vertically disposed shaft 35. This shaft ex- 100 tends down into a gear housing 36 and is provided near its lower end with a bevel gear 37 disposed in mesh with a similar pinion gear 38 on a horizontal shaft 39, which horizontal shaft is shown in Figures 2 and 18. 105

The horizontal shaft extends through the hollow pedestal 24, suitable bearings being provided therefor; and at an intermediate portion of the shaft 39 is a worm 40 disposed in mesh with a worm wheel 41 fixed upon a vertical central shaft 42. The lower end of the shaft 42 is carried in the spider arms 43,

shown in Figure 2, at the base of the hollow pedestal. The shaft 39 is driven by a suitable source of power (not shown). The shaft 39 will, therefore, rotate the spider construction which carries all of the molds, and it also serves to rotate the shaft 42 by which certain further operations in connection with the molding are carried out.

Referring to Figures 2 and 7, the outer ends of the spider arms are arranged to carry the mold transferring apparatus, and in the outer bearing portion 30 of each spider arm is placed a cylinder 44 having a plug 45 in its lower end through which is slidably fitted a plunger rod 46 carrying the plunger 47, which is fitted to reciprocate in the compressed air cylinder 48 secured beneath the flange 49 of said plug 45. The air connections to the cylinder 48 are shown at 50 and 51.

The upper end of the plunger rod 46 is pivotally coupled to a link 52 and this link is in turn pivotally coupled to a gear segment 53 rotating about a center 54 on an appropriate fixed part of the machine. The gear segment 53 meshes with a pinion 55 journaled above it upon a shaft 56. This pinion, or the shaft 56, carries an offset arm 57 to which the neck mold 58 is attached. As shown in Figure 7, by dotted lines, the arm 57 and neck mold 58 may be swung over at substantially 180°. The neck mold and arm 57 occupy initially the inner position, shown in full lines; that is, a position upon the inner circle of the machine. In this position the blank, indicated at 59 in Figure 7, is formed within the blank mold composed of the sections 60 and 61 carried by the clamp jaws 62 and 63. These clamp jaws are shown in Figures 14 to 17 inclusive and will be referred to later.

As shown in Figure 2, the blank mold is initially adapted to receive the charge of glass from an overhead source of supply or reservoir indicated at 64 by control of a valve plunger 65. A gob of glass is indicated as falling from the source of supply to the blank mold, it being received in the blank mold through the funnel 66 carried by the arm 67.

The glass is received in the blank mold to the quantity indicated in Figure 8, this glass body being indicated at 68. The neck mold 58 is shown as having received through its orifice the plunger 83 having the upper rounded head to form an initial cavity in the body of glass and to guide this body of glass, into the circular cavity of the neck mold 58. The plunger head 59 is carried upon the apparatus, shown in Figure 7, and this apparatus is intended to be withdrawn downwardly to permit the blowing apparatus 69, shown in Figure 9 to be applied beneath the blank mold. By this blowing apparatus 69 the blank is blown into shape, as shown in

Figure 9, the funnel 66 being previously withdrawn and the bottom mold plate 70 substituted therefor. The apparatus for accomplishing these results is shown in Figure 12.

After the operations shown in Figures 8 and 9, the sections 60 and 61 of the blank mold are separated, these sections being pivoted together and adapted to open out, as shown in Figure 1. This permits the neck mold and the blank or dummy to be swung over as indicated in dotted lines in Figure 7. When swung to the final position on the outer circle, the dummy will fit into the bottom mold plate 71 carried upon the arm 72. The dummy will also be in position to receive thereabout the semicircular mold sections 73 and 74 of the finishing mold, which mold sections are carried by the clamp jaws 75 and 76 illustrated in Figures 14 to 17, to which reference will be made later. The finishing operations are indicated in Figures 10 and 11. Figure 11 showing the blowing apparatus 77 applied to the neck mold 58 for the purpose of finally blowing the glass bottle 78 to shape.

In Figure 11 the blowing apparatus is shown as comprising a pipe 79 through which the air is delivered in a downward direction. The stream of air meeting the abutment 80 will be diverted to the peripheral edge of this abutment where passages are provided to admit the air around the edge and beneath the abutment to the cross passages 81 by which the air finally issues through the axial passage 82 and into the neck of the mold. This insures the gentle feeding of the blowing air.

Returning to Figure 7, the plunger head 83 is screw threaded or otherwise removably coupled to the plunger rod 84 movable through the operation of the plunger 85 which reciprocates in the cylinder 86. These cylinders 86 are carried upon spider arms 26, such spider arms being provided with openings 87 to admit air into the bases of the cylinders 86 beneath the plungers 85.

In Figure 7 is also shown the cam 88 carried by the arm 89 from the gear box 36. This cam encounters the roller 90 upon the lower end of the plunger valve 91, which is kept down to its seat normally by the spring 92, but which opens on raising of the valve to permit air to enter through the port 93 pass the valve and issue through the port 94.

Referring more particularly to Figures 14 to 17 inclusive, the clamp devices are shown for carrying the mold sections, but the mold sections are left off for the sake of clearness. The clamps 62 and 63 for the blank mold are at a higher elevation than the clamps 75 and 76 for the finishing mold as will be obvious from Figures 15 and 16 and from the positions which the two molds comparatively occupy, as shown in Figure 2.

These clamps are intended to be alternately opened and closed and they can, therefore, with economy in the manufacture and with simplicity in the operation be made in one piece. That is, one of the blank mold clamps 63 is made in one piece with one of the finishing mold clamps 76, while the other clamps 62 and 75 are made in another piece.

The unit 63, 76 is made with the spaced bearing rings 95 and 96, while similar bearing rings 97 and 98 are made upon the other unit. These rings are at the angle portions between the clamp jaws and such rings are intended to be nested together, so as to interfit, as indicated in Figure 17, and to all receive the cylinder 44, or some other appropriate turning post about which the clamp units may be swung. See Figure 1, for the various positions of these clamp units. The clamp units are further provided with the perforated ears 99 and 100 for the purpose of receiving the curved arms 101 and 102, shown in Figures 1 and 14. These curved arms are pivoted at 103 and 104 and they are provided with the straight tail pieces 105 and 106. Links 107 and 108 are pivoted to the tail pieces 105 and 106 and these links converge inwardly and are pivoted as indicated at 109 through a block 110 which block is slidable in the guide casing 111. The block is provided with a roller 112. The block 110 is provided with one or more lateral indentations 114 into which are urged by springs 115 the blocks 116.

The roller 112, as shown in Figures 1 and 2, bears against the cam flange 117 on the cam plate 118 extending about the upper portion of the hollow pedestal. The cam plate 118 is stationary and it is further provided with two other cam plates 119 and 120 which are secured to the cam plate 118 and extend beyond the cam flange 117 and above the same. These cams 119 and 120 are shown as of sector shape in Figure 1 and they only extend around a portion of the circumference of the machine corresponding to certain stages of the operations. The cams 119 and 120 are disposed in position to be engaged by a roller at the pivot point 109 between the links 107 and 108.

In Figures 5 and 6 is shown the guide plate having a ring 121 extending about the hollow pedestal, as shown in Figure 2. The ring 121 is provided with the V-shaped arms 122 and 123 between which are provided the radial slots 124. In these slots the side extensions 125 of the slide casings are fitted for radial movement, shoulders or seats 126 being provided in the slots 124 to receive the same. The parts 125 are shown in Figure 14 and there seating upon the shoulders is shown in Figure 1.

Reverting to Figure 7, the cylinder 86 is provided with an outstanding annular rib 130 upon which slides a casing 131 having a

port 132 near its upper end adapted to register with a port 133 in the blowing head 69. The registration of these ports is shown in Figure 9. In the exterior surface of this blowing head 69 is a groove 134 for receiving a washer 135 secured to the upper end of the casing 131. The lower end of the casing is provided with a bottom plate 136 against which works a coil spring 137 confined within the casing and abutting at its upper end against the rib 130 for the purpose of keeping the casing normally down and the ports 132 and 133 out of registry. Above the rib 130 and in the cylinder 86 is a port 138. Air is adapted to be introduced through this port, such air being received through the port 139 in the outer casing 131.

Referring again to Figure 2, at the upper end of the central shaft 42 is a head 140 rotating with the shaft and having a notched flange 141 extending from a low point thereon. A roller 142 is adapted to cooperate with these notches. This roller 142 is carried by a plunger 143, which slides in a cylinder 144 carried by the arm 145. In the cylinder is a plunger 146 for urging the roller into the notches. A coil spring 147 is engaged behind the plunger 146.

Loosely mounted over the rotating head 140 is a sleeve 148 by which the arm 145 is carried. This sleeve also carries at the opposite side, as shown in Figure 12, a support 149 for the arm 67. Such arm 67 carries the funnel 66 as previously described and it also carries above the funnel the guide way 150 for the slide 151 employed to close the funnel and having an apertured pin 152, this pin being used as a bearing for the arm 153. When the slide is in a closed state, compressed air is admitted through the hole in the pin 152 and into the funnel, thereby compressing the glass in the blank mold. The slide 151 is also shown in Figure 8. The slide is operated back and forth by a lever 153 fulcrumed at 154 upon an appropriate part and being actuated by a plunger 155 in a cylinder 156. Before the plunger 83 is removed, the slide 151 closes over the funnel and compressed air is admitted through the pin 152 on the slide into the blank mold, compressing the glass in said blank mold. At 157 is shown a cylinder having a piston 158 therein coupled to a piston rod 159 pivoted to an arm 160 upon the cam plate 118.

In the operation of the machine, the initial stage is shown at the right in Figure 2, where the blank mold is arranged beneath the source of supply with the funnel 66 in place thereabove and with the slide 151 in the position shown in Figure 12. The supply of glass is then permitted to drop into the blank mold up to substantially the level shown in Figure 8. The plunger 83, shown in Figure 8, is then removed by admitting air to the apparatus, shown in Figure 7,

through the ports 139 and 138, thus depressing the plunger 85 by which the plunger head 83 is carried. The air admitted through these ports also acts against the rigid rib 130 forcing the slidable casing 131 upwardly to cause registration of the ports 132 and 133 through which air is admitted to blow the blank into the condition shown in Figures 7 and 9. It will be understood that the ports 132 and 139 are connected to an appropriate source of compressed air supply.

Just prior to the blowing operation the funnel 66 is shifted away by operation of the piston 158 and cylinder 157, shown in Figure 12. As shown in this same Figure 12, the cylinder 157 is coupled to the arm 67 which carries the funnel 66.

The machine is continuously rotated, the stages of operation being noted approximately by the legends in Fig. 1. In the course of this movement, the mold sections 60 and 61 of the blank mold are opened out, for instance, as shown in Figure 1. This leaves the dummy 59 supported in the neck mold 58. Subsequently the neck mold is swung over, as shown in dotted lines in Figure 7, air for this purpose being admitted beneath the piston 46. This will bring the dummy to a position on the outer circle and following its arrival to this position, the finishing mold sections 73 and 74 are brought together upon the dummy. This swinging of the mold sections is accomplished by the cams acting upon the rollers 109 and 112.

The air blowing apparatus 77 is thereupon applied to the neck mold and the finished bottle blown. The bottle is subsequently removed by separation of the finishing mold sections.

It will be appreciated that due to the hollow column and hollow arm construction, cooling air may be circulated to all parts of the machine. It will also be appreciated that the design of the machine is simple in construction, light in weight and condensed so as to occupy a minimum of floor space with a minimum amount of parts, thereby reducing friction to a minimum.

The machine, because of these features, is able to operate at higher speeds than present types of similar machines. The machine will also have a wide working range capable of making a bottle of 1½" high to 15" in height on the same machine.

The head 140, Fig. 2, is affixed to the shaft 42, and is continuously rotating therewith. The arm 67 works freely around head 140, only when the roller 142 registers in one of the notches in disc 141. When the roller 142 registers into one of these notches, the arm 67 rotates until the head, or forward end of cylinder 157, comes into contact with the small valve attached to piston rod 159. This small valve directs the air into

the cylinder 144, which releases the roller 142 from the notches in disc 141, and at the same time admitting air into the rear of cylinder 157, this air bearing against the plunger 158 forces the arm 67 to its original position, under the flow of glass. This intermittent stroke of arm 67 is adjustable by moving the small valve on plunger rod 159, in either direction.

The function of roller 142, which snaps in the notches in flange 141, is to keep the arm 67, the funnel 66, and the baffle plate 70, which are mounted on arm 67, in perfect alignment with the blank molds underneath so as the different operations of forming the dummy in said blanks may be performed whilst the blank molds and arm 67, together with the parts mounted on said arm, are revolving with the machine. After the operation at Fig. 8 and Fig. 9 are performed, the roller is released from the notch, and arm 67 is brought to the preceding blank, that is when the roller snaps into the preceding notch.

The valve 91 shown at right-hand corner of Fig. 7 is used to direct the air into the blow head 77, which tends to blow the bottle into shape, shown more clearly in Fig. 11.

It is obvious that various changes and modifications may be made in the details of construction and design of the above specifically described embodiment of this invention without departing from the spirit thereof, such changes and modifications being restricted only by the scope of the following claims.

What is claimed is:—

1. A bottle forming machine comprising a hollow pedestal in communication with a source of air supply, a hollow spider in communication with the interior of the pedestal and revolvably carried by said pedestal, mold holding and transfer means carried by said spider, means for rotating said spider, a shaft in the pedestal, means to rotate said shaft, and a funnel carrying arm operatively carried on said shaft.

2. A bottle forming machine comprising a pedestal, a spider rotatably mounted thereon, sectional, blank and finishing molds, co-operating clamp units for holding said mold sections carried by said spider, said clamp units comprising right angularly disposed clamp jaws and spaced bearing rings at the angle portion between the jaws, a common pivot for the jaws of both units means engaging the units for opening and closing the jaws, means carried by said pedestal for shifting said last named means, and means for overturning the blank from one position into a second position during the shifting of said unit engaging means.

3. A bottle forming machine comprising a pedestal, with a spider rotating thereon, means for rotating said spider, mold holding

and transfer means carried by said spider, a head rotating independently of said spider on said pedestal, a funnel and mold plate carried by said head, a notched flange carried by the head, and a spring-pressed roller shiftable with the funnel and plate and engaging the notches in said flange.

4. A bottle forming machine comprising a blank mold, a neck mold thereunder, a plunger head adapted to be initially engaged through the neck mold, a plunger for operating said plunger head, a cylinder for said plunger, a casing floatingly supported about said cylinder, said casing and cylinder hav-

ing cooperating ports adapted to admit compressed air to the neck mold, yieldable means for normally shifting the casing to a position where said ports will be out of alignment, said casing and cylinder also having cooperating ports for admitting compressed air to said piston for driving the plunger head out of the neck mold and also for acting to shift said casing against the influence of said yieldable means whereby to bring about registry of said first mentioned ports.

ALBERT F. TREMBLAY.
